UNITED STATES PATENT OFFICE.

JOSEPH F. REIRDON, OF KINGSTON, PENNSYLVANIA, ASSIGNOR TO THE ADDER MACHINE COMPANY, OF WILKES-BARRE, PENNSYLVANIA, A CORPORATION OF PENNSYLVANIA.

PAPER-FEEDING DEVICE.

1,218,118.

Specification of Letters Patent.

Patented Mar. 6, 1917.

Application filed July 12, 1913. Serial No. 778,687.

To all whom it may concern:

Be it known that I, JOSEPH F. REIRDON, a citizen of the United States, residing at Kingston, Luzerne county, Pennsylvania, have invented new and useful Improvements 5 in Paper-Feeding Devices, of which the following is a specification.

This invention relates to paper feeding devices for use on calculating machines, and 10 typewriting machines, for instance, and constitutes an improvement on the invention disclosed in an application filed July 12, 1913, by Charles V. Wilgus, Charles E. Klink, and Joseph F. Reirdon, Serial No. 15 778,688.

In said application, a two-armed pawl drives a ratchet, step by step in one direction or the other, to advance or reverse the direction of feed of the paper. A single 20 drive means operates the pawl, and a shiftable latch determines which arm of the pawl shall be effective and the other idle.

This device, however, provides for a feed of constant degree, there being no means for 25 advancing or reversing the paper through more than a single line space interval.

One object of the present invention is to enable the paper to be fed through varying distances on either advance or reverse line 30 spacing, at the will of the operator, and to utilize in combination therewith, the ratchet and drive of the line space mechanism, disclosed in the application above referred to.

In rendering the line space mechanism 35 variable, I have changed the construction and operation of the line space mechanism from the form on which this invention is an improvement, the object being to improve such mechanism and obtain reliability and 40 accuracy in variable feeding in either direction.

As one means tending to these ends, I have arranged for a line spacing adjustment which leaves the positively operating 45 line space drive mechanism unaffected, and thereby dispenses with parts liable to break or get out of order.

Other objects and advantages will be more 50 fully disclosed hereinafter and particularly pointed out in the claims.

In the accompanying drawings, Figure 1 is an end view of the carriage of the well-known Wales calculating machine, equipped with one embodiment of my invention, the 55 device being at rest with the advance feed

pawl positioned for operation, and the line space adjusting mechanism set to permit the paper to advance a single line space;

Fig. 2 is a sectional view, showing the usual end plate removed, to disclose more 60 plainly the parts lying behind said plate;

Fig. 3 is a view similar to Fig. 1, but partly broken away and disclosing the positions of the parts at the end of the forward stroke of the drive means, the advance feed 65 pawl in engagement with the ratchet to turn it forwardly, and the line space adjusting mechanism set to permit the ratchet to advance three line spaces;

Fig. 4 is a similar view, showing the 70 mechanism at rest, the advance feed pawl being disabled or rendered ineffective, and the reverse feed pawl positioned for effective operation, the line space adjusting mechanism being set to enable a reverse 75 feed of two line spaces;

Fig. 5 is a view similar to Fig. 1, showing the reverse feed pawl disabled, the line space adjusting mechanism being set to disable the advance feed pawl, the parts being at 80 rest;

Fig. 6 is a rear view of that end of the carriage to which the invention is attached.

Fig. 7 is a detail perspective of the switch mechanism which disables the respective 85 pawls.

In the well-known Wales calculator, a carriage casting 1 (Figs. 1 and 6) having ways 2 supports a carriage 3, including end pieces 4 suitably connected by brace rods 5. 90 An axle 6 journaled in the end pieces, supports a platen 7, and a finger knob or twirler 8 (Fig. 6) fast on the axle, enables the operator to manually turn the platen forwardly or backwardly to advance or reverse the paper to bring a desired line to the printing point, or to insert and discharge the paper or work sheet.

Step by step advance of the paper or work sheet is accomplished mechanically 100 from a drive member or bar 9 connected to the usual main drive shaft (not shown), by which it is reciprocated. A yoke 10 on said drive member embraces a driven member which, in the present instance, is shown as a swinging bail 11 connected to a rock shaft 12 journaled in the end pieces 4.

This drive mechanism is shown in the above mentioned prior application.

The paper or work sheet is mechanically 110

- advanced step by step through the drive member 9, which on its forward stroke, swings the driven member 11 from the position shown in Fig. 1, to that shown in Fig. 5, and an angle lever or follower 13, 14, loose on the rock shaft 12, rocks with the driven member, due to a spring 15 which presses arm 13 of the angle lever toward the driven member or bail 11. The angle lever, 10 in turn, retracts an advance feed pawl 16 pivoted to the other arm 14 of said angle lever, to enable the pawl to bite upon a ratchet 17, preferably fast on the axle 6, preparatory to turning the axle and platen 7, (see Fig. 3). The usual spring 16^a presses the tooth of the pawl against the ratchet to insure its engagement therewith. The drive member 9, on its return stroke, restores the driven member 11 to its Fig. 1 position, 20 which latter member positively forces the angle lever 13, 14 rearwardly and upwardly to cause the pawl 16 to turn the ratchet and platen in the usual manner. A cam edge on the pawl 16 contacts a roll 16^b as the pawl 25 approaches the end of its effective stroke, to disengage the pawl from the ratchet, and permit the platen to be turned in either direction when the machine is at rest.
- If the follower 13, 14 and its pawl 16 participate of the complete forward stroke of the driven member, the latter on its return stroke, will operate through the pawl to turn the ratchet and platen through the maximum line space stroke, or say, three line space 35 intervals. It is desirable that this feed be varied to enable the paper to be fed through one or two line space intervals at will, or even to disable the paper feed.
- In applying a variable adjustment to the 40 line space mechanism, I desire to avoid interference with the drive and driven members 9 and 11 whose travel is constant and positive, and hence arrange the flexible connection between the follower 13, 14 and the driven member 11, and by arresting the follower at various points in its forward stroke, the retraction of the advance feed pawl 16 may be varied or eliminated, and the paper advanced through one or more steps, or allowed to remain idle.
- Such line space controlling mechanism includes a spring-pressed turn button 18 (of common form and hence not shown in detail) mounted on the end plate 4 and carrying a lock plate 19. A slip or pin and slot connection 20 enables the turn button to swing or oscillate a shiftable member 21 pivoted at 22 to the end plate 4. A series of graduated shoulders or abutments 23, 24, 25 55 and 26, preferably formed on one wall of an opening 27 in the member 21, are thus adjustable into and out of the path of a stop 28 on the follower 13, 14, which projects through the opening 27. Said abutments 60 arrest the stop at predetermined points in its

forward stroke to effect variations in the advance feed of the paper, depending upon the particular abutment brought to effective position.

Any one of a series of notches 29 on the lock plate 19, and corresponding with the abutments 23—26, fits over a pin 30 on the end plate 4 to hold the shiftable member where adjusted.

With abutment 24 in the path of the stop 28, (Fig. 1), the latter is arrested shortly after the follower 13, 14, starts on its forward stroke, and thus restricts the retraction of the pawl 16, and hence its active stroke, to the minimum effective degree, which permits a rotation of the platen through one line space interval only. The forward stroke of the driven member 11 is not affected, but the spring 15 is further tensioned after the arrest of the follower 13, 14. The driven member travels idly on its return stroke until it picks up the follower 13, 14, to restore the latter to its position of rest, (Fig. 1), and in so doing, propels the pawl 16 to drive the ratchet and platen one step or line space interval. When the abutment 26 is adjusted into the path of the stop 28, (Fig. 3), the drive and driven members being shown at the end of their forward strokes, it permits the maximum effective stroke of the pawl 16, thus feeding the paper through, say, three steps or line space intervals.

Fig. 5 shows the abutment 23 in the path of the stop 28 to lock the follower against the action of its spring 15, and thus disable the advance paper feed.

The same drive mechanism operates a back or reverse line spacing mechanism, shown most clearly in Figs. 2, 4, and 5, which mechanically steps the paper or work sheet backwardly instead of forwardly. An arm 31 fast on the rock shaft 12 operates a link 32 connected to one arm of a rocking lever 33 pivoted on a pin 34, the opposite arm of which rocking lever supports a back spacing or reversing pawl 35, adapted to engage the opposite side of the ratchet from pawl 16. A spring 36 tends to draw the reversing pawl toward the ratchet 17.

The reverse feed pawl 35 lies retracted, as shown in full lines in Fig. 4, when the machine is at rest. The drive member 9 on its forward stroke, swings the driven member 11 and, through the linkage 31, 32 and 33 just described, drives the pawl 35 against the ratchet 17, as indicated in dotted lines in Fig. 4, to turn the latter. An inclined prong or finger 37 on the pawl 35 rides up onto a displacing stud or bar 38 (see full lines Fig. 3) located in its path, as the reversing pawl approaches the end of its effective stroke, to disengage the pawl 35 from the ratchet 17, to prevent overthrow of the platen, such disengaging ac-

tion always taking place at a fixed point in the throw of the pawl.

5 The reverse feed pawl passes through a guard 39 on the carriage, which guard is shown in the form of a hook, (Fig. 6), to guide the pawl as it travels toward and from the ratchet, and prevent its accidental displacement.

10 The controller 18 which regulates the line spacing throw of the advance feed pawl 16, also governs the line space throw imparted by the reverse feed pawl 35 to the platen.

15 Spring 36 presses the pawl 25 against a gage 40 mounted on the line space controlling mechanism, as the lock plate 19, said pawl, when in operation, riding back and forth over the gage. Turning the controller 18 in one direction or the other, shifts the gage, mounted concentrically therewith, toward and from the pawl 35 to swing the latter toward or from the ratchet 17. Permitting the pawl to approach the ratchet, 20 enables the pawl, on its effective stroke, to more quickly engage the ratchet, to turn it and its associated platen through a greater arc than when the pawl is adjusted in the opposite direction.

25 The series of notches 29 correspond with the various positions to which the reversing pawl 35 is adjustable, and the graduated abutments 23-26 may be employed as an indicator to determine the desired adjustment of the reversing pawl, since the adjustments of both the advance and reverse feed pawls correspond. The gage 40, when 30 adjusted to the limit of its throw in one direction (see Fig. 5), prevents the engagement of the reversing pawl and the ratchet, the pawl traveling idly on the gage as the 35 drive member 9 reciprocates.

40 A switch mechanism 41 journaled on the pin 34, and comprising a plate having a pair of studs 42, 43, operates to disable either line space pawl while the other is operative. By 45 turning a spring-pressed switch-controlling button 44, (Fig. 6) fast on the switch plate 41, in one direction, the stud 42 is interposed in the path of the advance feed pawl 16 to prevent spring 16^a from pressing its 50 tooth against the ratchet, the pawl 16 in such case riding idly back and forth along the stud. The same movement of the switch shifts the stud 43 away from the reversing pawl 35 to free the latter to the action of its spring 36, and enable it to operate effectively. Shifting the switch in the opposite direction interposes the stud 43 in the path of the reversing pawl 35 and releases the advancing pawl 16 for effective operation. 55 One of the switch studs 42 is preferably elongated (Fig. 7) to fit into either of two seats 45 to hold the switch where adjusted.

60 The usual line space detent mechanism comprising a notched wheel 46 (Fig. 1) on the axle 6, and a spring-pressed detent 47

engaging said wheel, tends to prevent accidental overthrow of the platen in either direction due to momentum.

Changes may be made in the form and arrangement of the several parts set forth, 70 without departing from the spirit and scope on this invention.

What I claim as new, is:—

1. In a paper feeding device, the combination with a ratchet, and a platen turning therewith; of means to turn the ratchet in either direction, including an operating drive, having a stroke of constant length; a pawl adapted to be advanced by the drive to turn the ratchet in one direction, said pawl normally lying in advanced position; and a second pawl adapted to be advanced by said drive to turn the ratchet in the opposite direction, and normally lying in retracted position. 85

2. In a paper feeding device, the combination with a ratchet, and a platen turning therewith; of means to turn the ratchet in either direction, including an operating drive, having a stroke of constant length; a follower; yielding means connecting the follower and drive; means to arrest the follower at different points in its stroke; a pawl connected with the follower and normally lying in advanced position; and a pawl positively connected with the drive and normally lying in retracted position. 95

3. In a paper feed; the combination with a platen; of forward and backward line space feeding pawls; a ratchet common to both pawls; drive means likewise common to both pawls, and traversing a constant path; means to regulate the line space intervals when the platen is advanced; a separate means to regulate the line space intervals 100 when the platen is reversed; and a controller common to both line space regulating means.

4. In a paper feed, the combination with a platen, a ratchet, of line space mechanism, 110 including separate pawls, to advance or to reverse the paper step by step; and means contacted by the reverse feed pawl during its effective stroke, to disengage the pawl from the ratchet. 115

5. In a paper feed device, the combination with a platen and ratchet, and means to drive the ratchet and platen step by step in one direction; of a reversing pawl to engage the ratchet and reverse the platen step by 120 step; a finger on the reversing pawl; and a displacing member in the path of the finger and engaged thereby, to withdraw the reversing pawl from engagement with the ratchet, at a predetermined point in its 125 effective stroke.

6. In a paper feed device, the combination with a platen; a ratchet; and means to advance the ratchet and platen; of a reversing pawl to engage the ratchet and turn the 130

platen in the reverse direction; and a gage adjustable relatively to the pawl and contacted thereby to vary the line spacing intervals.

5. 7. In a paper feed mechanism, the combination with a platen of line space mechanism to advance and to reverse the platen, including a rotatable ratchet, and forward and reverse line spacing pawls; and a switch having disabling studs, one or the other of which is adapted to lie in the path of its corresponding pawl to render the latter ineffective.

15. 8. In a paper feed mechanism, the combination with a platen of line space mechanism to advance and to reverse the platen, including a rotatable ratchet and forward and reverse line spacing pawls; and a switch having disabling studs, one or the other of which is adapted to lie in the path of its corresponding pawl to render the latter ineffective; one of said studs seating in either of two sockets to hold the switch where adjusted.

25. 9. In a paper feeding device, the combination with a ratchet; and a platen turning therewith; of line space mechanism, including an operating member having a constant length of travel; a follower; means to yieldingly connect the follower and said member to press the follower toward the member; and a ratchet-driving pawl connected with the follower, said follower normally having a length of travel coincident with the operating member.

40. 10. In a paper feeding device, the combination with a platen, and a ratchet; of means to turn the ratchet, including a driven member; a follower normally tending to lie in contact with the driven member as the latter travels back and forth; a ratchet-driving pawl connected with the follower to travel therewith; and means to arrest the follower at different points in its following stroke, to vary the line spacing throw of the pawl.

50. 11. In a paper feeding device, the combination with a platen, and a ratchet; of means to turn the ratchet, including a driven member; a follower normally tending to lie in contact with the driven member as the latter travels back and forth; a ratchet-driving pawl connected with the follower to travel therewith; a stop on the follower; and adjustable means to arrest the stop at different points in its travel, to vary the line space intervals.

60. 12. In a paper feeding device, the combination with a platen, and a ratchet; of means to turn the ratchet, including a driven member; a follower normally tending to lie in contact with the driven member as the latter travels back and forth; a ratchet-driving pawl connected with the follower to travel therewith; a stop on the follower; an

adjustable member having a series of graduated abutments shiftable into and out of the path of said stop to arrest the follower at various points in its travel, and control the line space intervals.

70. 13. In a paper feeding device, the combination with a platen, and a ratchet; of means to turn the ratchet, including a positively driven member; a follower normally tending to lie in contact with the driven member as the latter travels back and forth; a ratchet-driving pawl connected with the follower to travel therewith; a stop on the follower; an adjustable member having a series of graduated abutments shiftable into and out of the path of said stop to arrest the follower at various points in its travel, and control the line space intervals; and means to set the adjustable member and lock it where adjusted.

75. 14. In a paper feed mechanism, the combination with a platen, and a ratchet; of means to turn the ratchet and platen in one direction or the other, including an operating member having a constant length of travel; a follower actuated thereby; means to vary the length of travel of the follower; a pawl connected to the follower to engage the ratchet and turn the platen in one direction; a second pawl to engage the ratchet and turn the platen in the opposite direction; and means to positively connect the second pawl and the operating member.

80. 15. In a paper feed mechanism, the combination with a platen, and a ratchet; of means to turn the ratchet and platen in one direction, including a drive member; a driven member positively rocked thereby in both directions; a follower coacting with the driven member; a spring to yieldingly press the follower toward the driven member; a pawl on the follower to engage the ratchet and turn the platen; and a second pawl operated from the driven member, to turn the platen in the opposite direction.

85. 16. In a paper feed mechanism, the combination with a platen; and a ratchet; of a feed pawl to turn the ratchet; drive mechanism for the ratchet having a constant travel; and means to vary the line space intervals, including a follower normally in contact with the drive mechanism; and means to detain the follower at different points in its travel irrespective of the drive mechanism.

90. 17. In a paper feed mechanism, the combination with a platen; a ratchet; and a feed pawl to turn the ratchet; of a follower connected with the pawl; a drive mechanism operable through a constant path to actuate the follower, and separable therefrom; and means to effect such separation.

95. 18. In a paper feed, the combination with a platen; and a ratchet; of drive mechanism operable through a path of constant length;

a follower adapted to contact the drive mechanism, and separable therefrom; means to detain the follower at different points in its travel; and a feed pawl driven from the 5 follower.

19. In a paper feed, the combination with a platen; and a ratchet; of drive mechanism operable through a path of constant length; a feed pawl; a follower to operate the pawl; 10 a yielding connection between the follower and drive mechanism tending to hold the follower in contact with the drive mechanism throughout its travel; and means to arrest the follower at different points irrespective of its yielding connection with the drive mechanism.

20. In a paper feed, the combination with a platen; and a ratchet; of drive mechanism operable through a path of constant length; 20 a feed pawl; a follower to operate the pawl, and normally in contact with the drive mechanism throughout its travel; and a line space adjusting member having a series of shoulders shiftable into the path of the 25 follower to arrest the latter at different points and thereby effect a separation between the follower and its drive mechanism.

21. In a paper feeding device, the combination with a platen; of forward and reverse line space mechanisms, including 30 pawls to turn the platen in one direction or the other; a driven member positively rocked in both directions and common to both pawls; a follower to operate with the 35 driven member and connected to one of said pawls; a stop on the follower; a shiftable member having a series of graduated abutments adjustable into and out of the path of the stop to vary the degree of rotation imparted by the last-named pawl to the ratchet; a controller having a slip connection with the shiftable member to adjust the latter; means to lock the controller where adjusted; a linkage connecting the 40 45 remaining pawl and driven member; means tending to shift both pawls to effective position; a switch mechanism to prevent the effective operation of either of said pawls and enable the other to operate; and a gage

adjusted by said controller to vary the degree of rotation imparted to the platen by said remaining pawl.

22. In a paper feeding device, the combination with a platen; of forward and reverse line space mechanisms, including 50 pawls to turn the platen in one direction or the other; a drive common to both pawls; a yielding connection between one of said pawls and the drive; adjustable means to arrest the pawl at different points, to vary 55 the line space interval through which the platen is turned by the pawl; a controller to govern said adjustable arresting means; and a gage also governed by said controller and operating the remaining pawl to vary 60 the line space interval through which said remaining pawl drives the platen.

23. In a machine of the character set forth, the combination with a platen; of line space mechanism therefor, including a 70 ratchet; advance and reverse feed pawls to turn the ratchet in one direction or the other; means to drive the pawls, having a path of constant length; and line space regulating mechanism comprising a series 75 of shoulders to arrest one of the pawls at various points in its retracting stroke; means shiftable relatively to the remaining pawl to vary the time of engagement of the pawl and ratchet; means to disengage the 80 last named pawl from its ratchet at a predetermined point in its effective stroke; and a single means to control the line space regulating mechanism of both pawls.

24. In a paper feeding device, the combination with a platen; of a ratchet; and line space pawls to turn the ratchet forwardly or backwardly; means to reverse the direction of rotation of said ratchet at will; drive mechanism for said pawls, traversing 90 a constant path; and means to vary the degree of rotation imparted by the pawls to the platen.

JOSEPH F. REIRDON.

In the presence of—

E. M. DETRICK,
RALPH S. WARFIELD.
